W. TURNER

COMBINED MOP AND WRINGER

Filed Sept. 13, 1926

Inventor

William Turner.

UNITED STATES PATENT OFFICE.

WILLIAM TURNER, OF LOUISVILLE, KENTUCKY.

COMBINED MOP AND WRINGER.

Continuation of application Serial No. 90,176, filed February 23, 1926. This application filed September 13, 1926. Serial No. 135,259.

My invention relates to a combined mop and wringer, and has a tension frame which permits a suitable mop cloth to be kept always spread out under tension when it is fastened to the frame so that it can be wetted and then semi-dried by pulling or pushing it between the spring controlled pressure tubular rollers of the wringer without having to touch it with the hands.

The specially designed tension frame is a necessary and principal adjunct of this improvement, as it keeps the mop cloth spread out, taut and elastic enough to absorb all necessary shocks in an extended frontal position with a downward frontal pressure tendency and automatically adapts and adjusts itself to the various postures taken and movements made by a person while using this mop; also it permits the mop cloth to be quickly and easily put on and taken off while it is placed between the two rollers of the wringer when needed.

The specially designed tension frame is so made that it will not scratch the surfaces of floors and furniture, etc., when a suitable mop cloth is attached to it.

Though these objects may be attained by various means and materials within the contemplation of my invention, I have sought in the accompanying drawings to illustrate only the most obvious and complete embodiment of my invention and if found advisable different pieces, parts or sections can be rigidly fastened together or altered in shape so as to simplify manufacturing them.

In the drawings the following are the figures and the parts they represent:

Fig. 1 represents a front view of the wringer attached to a mop handle with a mop cloth that is attached to the tension frame placed between the tubular rollers.

Fig. 2 represents a side view of the complete device with a mop cloth attached to it in one of the positions they will assume when in operation.

Fig. 3 represents the top view of the tension frame.

Fig. 4 represents a cross section longitudinally of a pressed in end bearing S of cylindrical shape having an axle hole R bored through the center of its closed end in which axle Q revolves; the other end's edge of the bearing S is flanged and shows the flange Y extended or made larger than the circumference of the top tubular roller O.

Corresponding letters of reference in the several figures of the drawings designate like parts.

Referring to the drawings, there is shown a handle A of suitable length and which is usually made of wood, the bottom end is cut out or slotted then covered and strengthened by a ferrule or piece of tubing B, so that the U or hairpin shaped extension or prong E, which projects from the central part of the top end of the rectangular shaped frame F of the device shown in Figs. 1 and 2, can be inserted and securely fastened in position by riveting with one rivet C.

The rectangular frame F was designed to avoid being cumbersome and to prevent the removal, unless force is used, of any of the tubular wringer's parts which are fastened to it. The bottom tubular roller M with its pressed in flanged bearings S uses the bottom side of the frame F as its axle; the top tubular roller O with its pressed in flanged bearings has an axle having eyelet hole ends P, so that the frame's F two sides can be slipped into them and act as supports and guides for the top tubular roller with its two regulating pressure springs I, and the two winged or knurled nuts H.

The pressed in end flanged bearings S as shown in Figs. 1 and 4 are of cylindrical shape with an axle Q placed in the axle hole R in the center of its closed end and the opposite or outside end's edge has a flange Y.

The extensions D placed at the bottom end of the mop handle A can be part of the ferrule B or top part of the frame F or be fastened on as a separate part, and are placed in that position so as to prevent the tension frame going too far back, if it should happen to slip from its fully extended position when in use. As a separate part by being made in the shape of an inverted T it can be pushed up into the bottom of the mop handle A and allow its inverted top part to extend over and above the top roller O and on both sides of the wringer, or the top middle part of the wringer's frame F can be projected to form extension D, or they can be made by flanging the bottom end of the strengthening ferrule B at the bottom of the mop handle A.

Fig. 3 gives a top or front view of the tension frame device; the narrow or oblong horizontal loop T at each end are bent upwards to an acute angle of about 45 degrees, so as to permit a suitable mop cloth to be easily slipped

through the openings W on to the top side of each loop, which alone fastens and keeps it in position, and then be brought or placed under the bottom side of each loop, thereby always putting a double thickness of material between the bottom part of each loop and the surface being mopped.

The two handles V placed at the ends of the tension frame enable any suitable mop cloth when fastened to it to be pulled or pushed through and between the two rollers M and O of the wringer thereby putting it into an extended frontal position alternately on each side of the bottom tube M.

As the two handles V are placed on a higher or raised position than the loops or ends of the tension frame the operator's hands do not have to come in contact with the mop cloth.

The gradual central curvature or bending downwards starting from the highest or raised part of each end of the tension frame shown in Fig. 2 prevents any sudden blow or hard push of its front extended end, against any obstacle, from bending or jumping upwards the two handles V and the central S shaped spring U.

The central spring U of the tension frame acts as a shock absorber, as well as giving the necessary elasticity to keep the mop cloth always taut and fully spread out in an extended frontal position.

What I claim as new and desire to secure by Letters Patent is:

1. In a mop of the character described a frame for a looped mop cloth comprising a single piece of wire bent at the ends to form flat loops for securing the cloth, said ends being offset from the intermediate portion of the frame, the wire being bent at the center into an S-shaped spring, straight shanks between the S-shaped spring and the respective ends mounting handles, one of the shanks being bent upwardly and at an obtuse angle to the spring member.

2. In a mop of the character described, a frame for a looped mop cloth comprising a single piece of wire bent at its ends to form loops for securing the cloth, said ends being offset from the intermediate portion of the frame, the wire being bent at the center into an expansive spring, shanks between the

spring and the respective ends mounting handles, one of the shanks being bent upwardly and at an obtuse angle to the spring member.

3. In combination with a mop frame having a mop fabric thereon, said mop fabric extending between wringer rollers with the rear end of said frame disposed above the rollers, a frame in which said rollers are mounted, a handle member carried by said roller frame a member carried by the handle in the path of the mop frame and positioned whereby upon rearward movement of the mop frame incident to pressure on the front end thereof during a mopping operation and sliding of the mop fabric between the rollers, said projection will engage the mop frame and limit its rearward movement.

4. The combination in a mop, of a handle, a mop carrying means secured to said handle, a mop cloth, and a mop cloth frame for holding said cloth taut while in operative position, said cloth forming the sole connection between said carrying means and said frame.

5. The combination with a mop, of a handle, relatively adjustable rollers carried by said handle, a mop cloth disposed between said rollers, and an independently movable frame carrying said mop cloth forming means whereby said mop cloth is held taut and whereby the mop cloth may be moved back and forth between the rollers.

6. The combination in a mop, of a handle, rollers carried by said handle, a mop cloth disposed between said rollers, an independently movable frame carried by said cloth, and gripping handles carried by said frame forming means whereby the frame may be moved back and forth to move the cloth between the rollers.

7. The combination in a mop, of a handle relatively adjustable wringing rollers carried by said handle, a mop cloth disposed between said rollers, an independently movable frame mounting the opposite ends of the mop cloth with the mop cloth disposed between said rollers and the opposite ends of said frame disposed on opposite sides of the rollers, said frame having a flexible intermediate portion for normally holding the mop cloth taut.

WILLIAM TURNER.
